UNITED STATES PATENT OFFICE.

HARDMAN A. EARLE, OF LONDON, AND PERCY WALTER DRUITT, OF THE COUNTY OF SURREY, ENGLAND.

APPARATUS FOR COMPOSING AND CASTING TYPE.

1,153,049.

Specification of Letters Patent.

Patented Sept. 7, 1915.

Application filed May 31, 1913. Serial No. 771,043.

To all whom it may concern:

Be it known that we, HARDMAN ARTHUR EARLE and PERCY WALTER DRUITT, both subjects of the King of Great Britain, residing, 5 respectively, in London, England, and Surrey, England, and whose post-office addresses are, respectively, Knightsbridge Mansions, in the county of London, England, and Baron Cottage, London Road, Mitcham, in 10 the county of Surrey, England, have jointly invented certain new and useful Improvements in Apparatus for Composing and Casting Type, of which the following is a specification.

15 This invention relates to apparatus for composing and casting type wherein two or more magazines are provided for the purpose of accommodating a larger assortment of matrices, and has for its primary object 20 to provide improved means for separating the matrices into groups and delivering them to their respective magazines.

According to this invention the separation of the matrices according to letter character and also according to font or group is effected partly in customary manner by 25 means of co-operating teeth combinations on a single distributor bar and the matrices and partly by means of a guide or receiver 30 oscillating in timed relation with the progression of the matrices along the distributor bar, which guide is adapted to receive matrices of different groups as they drop from any distributor bar at successive 35 phases of movement and guide them to their appropriate magazines which are ranged alongside each other. Thus by giving the distributor bar in customary manner an eighth tooth combination of matrix-sus- 40 taining teeth and making provision for the discharge of matrices from the bar at every $\frac{1}{8}$ of an inch or every half revolution of the distributor worms instead of at every $\frac{1}{4}$ inch interval or every complete revolution of the 45 worms as has been the usual practice heretofore, double the number of matrices can be distributed by a bar of given length. Moreover, although the number of release points along the bar is thus doubled, this invention 50 enables an equal number of receiving channels to be used without sacrificing any of the requisite width of the individual channels.

The invention is illustrated in the accompanying drawings, wherein—

55 Figure 1 is a side elevation with part

broken away showing one construction of the improved distributing device; Fig. 1^a is a part plan view showing the relation of the inlet openings of the oscillating chutes which guide the two groups of matrices into their respective magazines; Fig. 2 is a right hand elevation; Fig. 3 is a vertical transverse section; Fig. 4 is a part view corresponding with Fig. 1 showing a modified arrangement of matrix chutes; Figs. 5, 6 and 7 are part views corresponding with Fig. 3 but showing several modifications in the construction of the oscillating matrix guide and associated parts.

The conveying of the different groups of 70 matrices into their respective magazines is effected by means of an oscillating guide pivoted at *a* and extending the whole width of the magazines and provided on either side with chutes *b*, *c* for receiving and guiding 75 the matrices *d* to the appropriate channels *b*^o, *c*^o of their respective magazines *b*', *c*', the chutes along one side being staggered with respect to those on the other, as shown more particularly in Fig. 1^a. Further, the 80 two groups of chutes may be inclined to the vertical oppositely to each other as shown in dotted lines in Fig. 1, so as to bring the lower ends of the chutes on the two sides into the same planes and into correct registration with the uniformly spaced channels 85 of the two magazines, which channels are preferably throughout their whole length, and necessarily at their lower or outlet ends, in register with each other in the respective 90 magazines. Alternately the chutes *b*, *c* may be vertical (Fig. 4) and the stationary guide channels *b*^o, *c*^o which, for convenience, are interposed between the oscillating chutes *b*, *c* and the magazine proper *b*', *c*', may 95 have their walls oppositely inclined to the vertical with the same object, as shown in dotted lines in Fig. 4.

The oscillating guide is so correlated with the conveyer worms *e*, *e*', *e*² of the distributor as to make one stroke for each half revolution of the conveyer worms and thereby bring alternately each group of matrix chutes *b*, *c* into the correct position to receive the matrices from the distributor bar *f* and guide them into the respective magazines.

With a distributing apparatus for multiple magazine machines operating as above described, it becomes unnecessary for the 110

matrices belonging to one group to be distinguished from those of the other group otherwise than in the combination of the serrations f' which is formed thereon for cooperation with the teeth of the distributor bar.

Motion may be imparted to the oscillating guide b, c from a cam g rotating synchronously with the distributor screws e, e', e'' by means of a cam lever h and link i connected with a lever j journaled on the axle a of the oscillating guide, this latter lever being spring-connected through a spring m with another lever k adjacent to it and fast on the axle a of the oscillating guide, in such manner that should the guide b, c meet with any abnormal resistance to its movement the spring m will yield and thereby obviate damage to the mechanism. The correct angular relation of the two levers is determined and maintained by means of an adjustable stop n .

Provision may be made for holding the oscillating guide in either extreme position when it is desired to use the apparatus as a single magazine machine. This may be effected, as shown more particularly in Fig. 2, by means of a pair of swing props or struts o, p the former of which serves to hold the roller h' of the cam lever h off the surface of the cam g when swung into engagement with the tail of lever j , as shown in dotted lines in Fig. 2. The lever k , and consequently the axle a , under the tension of the spring m assumes its normal relation to the lever j , and consequently the chute c is and remains, in these circumstances, in position to receive the matrices from the distributor. Should, however, the strut p be also swung into the position in which it engages the tail of the lever k , this lever, and consequently the axle a , is held in the position in which the chute b receives the matrices from the distributor.

As shown in Fig. 3 the chutes b, c are made separately and are complete in themselves with side walls q and the internal partitions forming the various compartments for the different matrices, the chutes being separately assembled on the axle a and pinned to each other to form a rigid structure in any suitable manner.

In the modification shown in Fig. 5 the partitions project on either side in staggered relation from a central longitudinal plate or beam r and the lower edges of this beam and of the partitions are circular and struck from the axis a of the oscillating beam, the upper edges of the fixed guide chutes b', c' being circular and struck from the same center. As in the construction of Fig. 3, the outer side walls q are secured by suitable means upon the outer edges of the partitions of the chutes.

In the construction of Fig. 6, the chutes

b, c themselves are formed as a single integral structure as in Fig. 5, but the outer side walls q are removed from the oscillating part of the mechanism, and are replaced by upward extensions q' of the outer walls of the stationary chutes or guide channels b', c' . It will be seen that this construction involves an angular separation of the walls q which leaves a gap between the vertical edge of the receiving chute (for the time being) and the extension q' which forms the outer side wall of the same. To obviate this defect, as shown in Fig. 7, the oscillating chute structure is made cylindrical in form and the side walls q'' , which are separate from the chute, form parts of a cylinder the axis of which is the axle a of the chutes b, c and the radius of which is slightly greater than that of the partition plates of the chutes. The side walls q'' are hinged either to the upper edges of the side walls of the fixed channels b', c' , or as shown independently thereof, for the purpose of readily assembling the parts and obtaining access to the chutes b, c . Further, it may be arranged to oscillate the walls q'' synchronously with the chutes b, c should it be desirable to do so. The construction of Fig. 7 might be further modified to eliminate the stationary channels b', c' entirely, the diameter of the oscillating chutes being suitably increased to provide the requisite length of guide channels and the inlets of the magazines being formed on the curve like those of the channels b', c' in Figs. 5, 6 and 7.

Having now particularly described and ascertained the nature of our said invention and in what manner the same is to be performed, we declare that what we claim is:

1. A multiple magazine type composing and casting machine having a type distributor which comprises means whereby matrices belonging to different magazines are discharged in succession from the distributor bar at different phases of revolution of the conveyer worms and an oscillating guide arranged with its axis extending the whole width of the magazines and provided on each side of the axis with a group of chutes for the reception of the matrices and means for oscillating the guide in synchronism with a prearranged partial revolution of the conveyer worms thereby bringing each group of chutes into position to receive the matrices from the distributor bar and divert them into their appropriate magazines, substantially as described.

2. A multiple magazine type composing and casting machine having a type distributor which comprises an oscillating guide formed with two longitudinal compartments each with a row of chutes for receiving and guiding the matrices to the appropriate channels of their respective magazines, the chutes in the two compartments

being staggered at their receiving ends, and a single distributor bar arranged to deliver matrices to both of said compartments.

3. A multiple magazine type composing and casting machine having a type distributor which comprises an oscillating guide formed with two longitudinal compartments each with a row of chutes for receiving and guiding the matrices into the appropriate channels of their respective magazines, the chutes in the two compartments being staggered at their receiving ends, a single distributor bar arranged to deliver matrices to both of said compartments and two sets of stationary guide channels interposed between the oscillating guide and the magazines.

4. A multiple magazine type composing and casting machine having a type distributor which comprises a distributor bar, conveyer worms coöperating with the bar, means whereby the matrices belonging to different magazines are discharged in succession from the distributor bar at different phases of revolution of the conveyer worms, an oscillating guide having two rows of chutes, and two sets of stationary guide channels forming a continuation of said chutes and leading to the compartments of two magazines, substantially as described.

5. A multiple magazine type composing

and casting machine having a type distributor which comprises a distributor bar, conveyer worms coöperating with the bar, means whereby the matrices belonging to different magazines are discharged in succession from the distributor bar at different phases of revolution of the conveyer worms a cam rotating synchronously with the conveyer screws, an oscillating guide driven by the said cam and mechanism comprising a pair of levers yieldingly coupled, substantially as described.

6. A multiple magazine type composing and casting machine having a type distributor which comprises a distributor bar, conveyer worms coöperating with the bar, means whereby the matrices belonging to different magazines are discharged in succession from the distributor bar at different phases of revolution of the conveyer worms an oscillating guide and means for holding said guide in either extreme position, substantially as described.

In testimony whereof we have signed our names to this specification in the presence of two subscribing witnesses.
